UNITED STATES PATENT OFFICE

2,310,714

GOOSENECK FOR CONTAINERS

George H. Slaughter, Benton Harbor, Mich.

Application October 11, 1941, Serial No. 414,619

4 Claims. (Cl. 221—74)

This invention relates to goosenecks for containers, and its principal object is to provide a gooseneck which may be easily and thoroughly cleaned, and in the event that any of its restricted passageways or ducts become clogged, they may be readily cleared of the obstruction.

The main difficulty which has been heretofore encountered in goosenecks in which the several parts are integrally united, is the difficulty of clearing the passageways and ducts of matter which clogs them. Usually this requires the services of an expert, and when the gooseneck becomes clogged, it is sent to a service station for cleaning.

One of the objects of this invention is to provide a gooseneck in which any obstruction in any of the restricted passageways or ducts may be easily cleared by unskilled persons.

Another object is to provide a gooseneck for containers and composed of separable parts which may be readily disconnected for the purpose of cleaning them and clearing the passageways and ducts of any matter that clogs them.

Another object is to provide a gooseneck of this character for use on containers such as bottles, jars and the like, and arranged to be connected to an air line and a fluid conducting line for conducting fluids (liquids) to and from the container under the influence of minus or plus pressure, which is supplied to the container through the air line by a vacuum pump or a pressure pump, as the case may be.

With these and other objects and advantages in view, this invention consists in the several novel features of construction, arrangement and combination of parts hereinafter fully set forth and claimed.

The invention is clearly illustrated in the drawing accompanying this specification in which:

Fig. 1 is a central vertical section through a container, partly broken away, and equipped with a gooseneck embodying a simple form of the present invention;

Fig. 2 is a detail central vertical section of the gooseneck alone;

Fig. 3 is a detail horizontal section taken on the line 3—3 of Fig. 2;

Fig. 4 is a plan of a certain sleeve member forming part of the device; and

Fig. 5 is a side elevation, partly broken away, of a slightly modified form of a tubular member which comprises part of the device.

Referring to said drawing, and first to Figs. 1 to 4, inclusive, the reference character 6 designates a container such as a bottle, jar or the

like, here shown in the form of a glass bottle having a neck 7. The gooseneck, designated generally by the reference character 8, is supported in an opening in the container and the joint between the gooseneck and container is hermetically sealed to prevent air from leaking into or out of the container. When a bottle is used, a rubber stopple 9 is employed between the gooseneck and neck of the bottle.

10 In the form of the invention illustrated, the gooseneck comprises a tubular member 10, and a sleeve member 11, surrounding the tubular member and having a threaded connection therewith whereby the two may be readily connected and disconnected. The tubular member is somewhat longer than the sleeve member and each end is provided with a tapered enlargement 12, whereby flexible tubes 13, 14 may be attached to the tubular member. The flexible tube 13 leads to a suitable container, surgical instrument, or other object or place, from which liquid is to be drawn into the container on which the gooseneck is used, or to which it is to be conducted from said container. The flexible tube 14 leads from the lower end of the tubular member 10 to a point adjacent the bottom of the container 6.

15 The sleeve member 11 is formed at its upper end with a head 15, from the lower side of which depends a sleeve 16, which is of a slightly greater internal diameter than the external diameter of the tube portion 17 of the tubular member 10, to provide an annular air passageway 18 between the sleeve 16 and tube 17.

20 The annular air passageway is open at its lower end and terminates at its upper end within the head 15, and leading from said passageway within the head is a duct or port 19, which in accordance with the form of the invention illustrated extends at right angles to the axis of the tube and opens out through the side face of the head. A threaded nipple 20, having the usual tapered enlarged end for attachment to a flexible tube 21, is threadedly secured in the head in open communication with the duct or port 19. 25 The flexible tube 21 is connected to a source of vacuum supply or air pressure.

25 The head 15 is provided with internal screw threads 22 in the bore of its upper portion and the tubular member 11 is formed with a reduced externally screw-threaded neck 23 that is screwed into the screw-threaded bore of the head. The upper face of the head may be provided with a depression 24 to receive a gasket or washer 25 for making a leak-proof joint between the tubular member and sleeve member. Both of

said members have knurled faces, whereby they may be firmly grasped when assembling or separating the two members of the device.

In the modified form illustrated in Fig. 5, the upper end of the tubular member 10^a is provided with a tube 10^b which is bent upon itself into a somewhat U-shape and provided upon its extremity with the usual tapered enlargement 10^c, whereby a flexible tube may be connected to it. In other respects the construction of the device is substantially the same as that of the preferred form.

In the operation of the gooseneck, the flexible tube 21 is connected to a pump, either a pressure pump or vacuum pump, as the case may be. When the device is used to convey liquid from the container to some remote place, a pressure pump is employed and the pressure within the container is raised sufficiently to force the liquid out of it. The air from the pump enters the duct or port 19 through the nipple 20 and passes down through the annular passageway 18 and into the container, thereby forcing the liquid up through the flexible tube 14, the tubular member 10, and flexible tube 13, to the place where it is to be delivered.

When used to convey liquid to the container, a vacuum pump is connected to the flexible tube 21 and a partial vacuum is created in the container, the flexible tube 14, tubular member 20, and flexible tube 13, thereby causing the liquid to flow from its source to the container.

In devices of this character, solids are likely to gather in the restricted passageways and ducts, thus obstructing the flow of air. Whenever an obstruction occurs in the present device, the tubular member and sleeve member may be readily separated from each other and a wire or other slender object may be thrust through the hole in the nipple 20 and through the duct or port 19, thereby dislodging any obstruction therein. Furthermore, with the parts separated, all surfaces thereof may be readily and quickly cleaned.

More or less variation of the exact details of construction is possible without departing from the spirit of this invention; I desire, therefore, not to limit myself to the exact form of the construction shown and described, but intend, in the following claims to point out all of the invention disclosed herein.

I claim as new and desire to secure by Letters Patent:

1. A gooseneck for containers, comprising a tubular member arranged at each end for connection with a flexible tube, one tube adapted to extend down into the container and the other one leading away from the other end of the tubular member, a sleeve member surrounding the tubular member with the latter projecting beyond both of its ends and having a head at its upper end and a sleeve therebelow, the tubular member and sleeve member being threadedly secured together, and there being an annular passageway between the tubular member and sleeve member extending down from a point within the head, and there being a duct in said head leading outward from said passageway, a nipple secured in the head in communication with said duct and adapted for connection with a flexible tube which

is adapted to be connected to a pump, and sealing means between the sleeve member and container.

2. A gooseneck for containers, comprising a tubular member arranged at each end for connection with a flexible tube, one tube adapted to extend down into the container and the other leading away from the other end of the tubular member, a sleeve member surrounding the tubular member with the latter projecting beyond both of its ends and having a head at its upper end and a sleeve therebelow, there being a screw-threaded connection in said head between the tubular member and sleeve member, and there being an annular passageway between the tubular member and sleeve member below said screw-threaded connection, and there being a duct in said head leading outward from the passageway, a screw-threaded nipple secured in the head in communication with said duct and adapted for connection with a flexible tube which is adapted to be connected to a pump, and means for hermetically sealing the sleeve in the container.

3. A gooseneck for containers, comprising a tubular member arranged at each end for connection with a flexible tube, one tube adapted to extend down into the container and the other one leading away from the other end of the tubular member, a sleeve member surrounding the tubular member with the latter projecting beyond both of its ends and having a head at its upper end and a sleeve therebelow, there being a screw-threaded connection in said head between the tubular member and sleeve member, a stopple surrounding said sleeve and adapted to hermetically seal the same in the container, there being an annular passageway between the tubular member and the sleeve member below the screw-threaded connection, and there being a duct in said head leading outward from the passageway, and a nipple secured in the head in communication with said duct and adapted for connection with a flexible tube which is adapted to be connected to a pump.

4. A gooseneck for containers, comprising a tubular member arranged at each end for connection with a flexible tube, one tube adapted to extend down into the container and the other one leading away from the other end of the tubular member, said tubular member being formed with an annular shoulder intermediate its ends, a sleeve member surrounding the tubular member with the latter projecting beyond both of its ends and having a head at its upper end and a sleeve therebelow, the tubular member having a screw-threaded neck below said annular shoulder threadedly secured in the head of the sleeve member, a gasket between the annular shoulder and head of the sleeve member, a stopple surrounding said sleeve and adapted to hermetically seal the same in the container, there being an annular passageway between the tubular member and the sleeve member below the screw-threaded connection, and there being a duct in said head leading outward from the passageway, and a nipple secured in the head in communication with said duct and adapted for connection with a flexible tube which is adapted to be connected to a pump.

GEORGE H. SLAUGHTER.
